UNITED STATES PATENT OFFICE

146,409

DESIGN FOR A PIPE THREADING TOOL

Thomas R. Jones, Chicago, Ill., assignor to Nye
Tool & Machine Co., a corporation of Illinois

Application October 27, 1945, Serial No. 123,242

Term of patent 14 years

(Cl. D54—14)

To all whom it may concern:

Be it known that I, Thomas R. Jones, a citizen of the United States, residing at Chicago, county of Cook and State of Illinois, have invented a new, original, and ornamental Design for a Pipe Threading Tool, of which the following is a specification, reference being had to the accompanying drawing, forming a part thereof, in which:

Fig. 1 is a top plan view of the threading tool; Fig. 2, an elevational view; Fig. 3, a bottom plan view; Fig. 4, an end elevational view; and Fig. 5, an end elevational view from the opposite end shown in Fig. 4, showing my new design.

I claim:

The ornamental design for a pipe threading tool, as shown.

THOMAS R. JONES.
